UNITED STATES PATENT OFFICE.

SAMUEL E. GUINN, OF JOHNSON CITY, TENNESSEE.

DESIGN FOR A VANITY CASE.

Application filed February 7, 1928. Serial No. 25,255. Term of patent 3½ years.

To all whom it may concern:

Be it known that I, SAMUEL E. GUINN, a citizen of the United States, residing at Johnson City, in the county of Washington and State of Tennessee, have invented a new, original, and ornamental Design for a Vanity Case, of which the following is a specification, reference being had to the accompanying drawings, forming part thereof, and in which the figure is a perspective view of a vanity case showing my new design.

I claim:

The ornamental design for a vanity case, as shown.

SAMUEL E. GUINN. [L.S.]
